Patented Sept. 8, 1914.

UNITED STATES PATENT OFFICE.

HENRY P. DWYER, OF SAN FRANCISCO, CALIFORNIA, ASSIGNOR TO DWYER WIRELESS TELEPHONE AND TELEGRAPH COMPANY, OF SAN FRANCISCO, CALIFORNIA, A CORPORATION OF DELAWARE.

WIRELESS OSCILLATOR.

1,109,909.

Specification of Letters Patent.

Patented Sept. 8, 1914.

Application filed August 5, 1912. Serial No. 713,275.

To all whom it may concern:

Be it known that I, HENRY P. DWYER, a citizen of the United States, residing at San Francisco, in the county of San Francisco and State of California, have invented new and useful Improvements in Wireless Oscillators, of which the following is a specification.

The present invention relates to an improved oscillator for generating electromagnetic waves for use in wireless telegraphy, telephony, and for all other purposes for which said waves can be employed.

The object of my invention is to provide such an oscillator which will generate undamped electric oscillations of great length, and which will be practically free from interruptions or discontinuity.

In the accompanying drawing, the figure 20 is a vertical sectional view of my improved oscillator.

Referring to the drawing, 1 indicates a chamber, through a bearing 2 in the upper portion of a wall of which can slide a horizontal portion 3 of a carrier 4, the inner end of the horizontal portion being connected to the upper end of a vertical portion 6, the lower portion of which is connected to one end of a horizontal member 7, on the other 30 end of which is carried a rotatable ring 8, in which are a suitable number, as four, of tubular cathode holders 9 supporting horizontally extending cylindrical hollow cathodes 11, preferably formed of aluminum.

Adjacent to the cathode surface of the lowermost of these cathodes is the surface of a cylindrical anode 12, which is in the form of a tube of copper or other suitable conductor, passing through a bearing 13 in a lower portion of the wall of the chamber. A tube 14 extends centrally and longitudinally through the tube 12 and connects at its inner end with a small central aperture formed in the closed end of the tube 12, which forms the 40 surface of the anode. A needle valve 22 controlled by a stem 23 regulates the size of the passage through said aperture. The outer end of said tube 14, outside the tube 12, is connected by a pipe 10 with a pump 16 to

50 which a pipe 17 leads from a chamber 18, containing a suitable liquid, preferably a monohydric alcohol, there being commonly used in practice denatured alcohol. A tube 19 also connects the bottom of the chamber 1

with the alcohol chamber 18. Brine pipes 5 55 in this chamber maintain the alcohol at a very low temperature. From the pipe 10 a pipe 15 leads to a rotary pipe joint 30 within the chamber 1 above the liquid level, from which joint depends a pipe 35, the lower portion of which passes within the hollow cathode in use, so that cold alcohol flowing out of the open lower end of said pipe 35 discharges against the rear or inner surface of the cathode and then flows out at its rear 60 end into the chamber 1. The chamber 1 is filled nearly up to the level of the horizontal portion 3 of the holder with the before-mentioned liquid. Said tubes 12 and carrier 4 are connected to opposite sides of the circuit 70 through the oscillator by means of binding posts 20, 21, respectively. The interior of said tube 12 is maintained cool by the circulation of cold water entering said tube by a water inlet pipe 24 leading almost to the extreme inner end thereof, the water escaping from said pipe by a water outlet conduit 25 connected with the outer end of said tube 12. 75 26 indicates a brine coil in the upper portion of the chamber 1, below the level of the alcohol, suitably connected outside said chamber to a source of supply of brine, so that the brine is maintained in constant circulation in said coil.

To strike the arc between the anode and cathode, there is provided upon the horizontal portion 3 of the carrier 4, outside the chamber 1, a collar 27 secured by a set screw 28, and having outwardly extending pins 29, which are engaged by the grooved ends of a 80 yoke 31, formed in an end of a lever 32, pivoted upon a suitable base 33. Against said lever can press a stem 34, passing through the wall 36 of the oscillator chamber, and formed at the outer end with a push knob 37. 90 Through said lever 32 passes a horizontal adjusting rod 38, having secured thereon a collar 39 bearing against the outer side of the lever, an end of the rod 38 being screwed into a socket 41, provided upon the wall of the chamber 1. Said rod extends through said wall 36, and upon the outer end is formed a handle 42, by which it may be turned. A coiled spring 43 is compressed between said socket and a washer 44 loose 100 around the rod. It will be seen that with this construction, by pushing the lever inward by means of the stem 34 against the pressure of

said spring 43, the carrier can likewise be pushed inward, and the cathode can be brought in contact with the anode, and the circuit therebetween closed. On removing the pressure from the knob 37, the spring causes the cathode to be withdrawn from the anode, whereupon a spark is formed therebetween. The distance to which it can be thus withdrawn may be varied by turning the rod 38 by means of the handle 42, and thus varying the distance of the collar 39 from the socket 41.

45 is a vent opening through the top of the chamber, and 46 is a window in said top, through which the arc between the anode and cathode can be inspected.

In order to withdraw one cathode when worn out by use and to substitute a new cathode, there is secured to the disk 8 a bevelled gear 48, which meshes with a bevel gear 49 on a shaft 51 guided in bearings 52 on the vertical portion 6 of the carrier. The upper end of said shaft carries a bevel gear 53, which meshes with a bevel gear 54, upon 20 the end of a shaft 56 extending centrally through the horizontal portion 3 of the carrier, to the outer end thereof, and having attached to its end a crank arm 57, by which, after the tube 35 has been withdrawn from the hollow cathode, which can be done by means 25 of a link 40 attached to the upper end of an arm 50 rotatable with the depending pipe 35, said link 40 passing through the wall 36, said cathode may be turned, thereby also revolving the cathode carrier so as to bring the 30 next cathode into the proper position opposite to the anode. The tube 35 is then moved back into place in said cathode. The gearing is preferably such that one revolution of 35 the crank arm is just sufficient to bring the succeeding cathode into such position.

The arc obtained by my oscillator through a liquid such as alcohol changes its position between the electrodes with each passage of the arc, always shifting in a counter-clockwise direction looking from the anode to the cathode, the shift being through a substantially uniform distance in each case, so that in course of time, say, about a week, the 45 cathode is covered with minute pits or indentations of practically uniform depths. From my observations the shift of the path 50 of the arc is always to the left and through a substantially uniform distance, and I believe that this phenomenon is related to the fact that alcohol is an optically active liquid. Of course, good results cannot be obtained with an electrolytic liquid, which is not a dielectric, and such optically inactive 55 electric liquids as water and oil give very poor results. While by an experimental plant in San Francisco perfect wireless telephonic communication has been maintained with Los Angeles, a distance of 490 miles, 60 for a continuous run of 6 hours without

"fading," or "frying," using alcohol, such liquids as oil and water, with the same apparatus, gave damped oscillations, so that scarcely an intelligible sound was heard at all.

70 The arc is not a true vapor arc, such as is observed between carbons in air or gas, but is more like a convective or brush discharge of extremely high frequency.

A long series of experiments has demonstrated that a direct current of six and a half amperes on five hundred volts can be maintained through four arcs of this character in series using alcohol with a drop of but forty volts, or ten volts to an arc. The 75 arc therefore generates but little heat, and but a small current of water circulating in my positive electrode keeps the electrode cool and the liquid temperature extremely low, the negative electrode showing no 80 signs of heat and but little wear.

I regard the utility of my oscillator as being due, in a great measure, to the central discharge of cold alcohol upon the surfaces of the cathode, the alcohol being also maintained cold by the circulation of brine in the 85 brine pipes. This impact of cold alcohol upon the surfaces of the cathode, and the passage thereof between the anode and cathode, serve to maintain the electrodes always 90 at the necessary low temperature required for the most effective discharge of the arc.

A further important effect of the flow of the alcohol between the electrodes is to remove from that region any metallic particles which may be removed from the electrodes by the passage of the arc, thereby 100 maintaining the oscillations of reliable uniformity.

I claim:—

1. An oscillator comprising a liquid, electrodes immersed therein, one of said electrodes having an aperture and the other having a surface opposite to said aperture and means for producing a continuous flow 110 of said liquid through said aperture.

2. An oscillator comprising alcohol, electrodes immersed therein, one of said electrodes having an aperture and the other having a surface opposite said aperture, 115 and means for producing a continuous flow of alcohol through said aperture.

3. An oscillator comprising alcohol, electrodes having electrode surfaces immersed therein, one of said electrode surfaces having an aperture opposite to the center of the other electrode surface, and means for producing a continuous flow of said alcohol through said aperture.

4. An oscillator comprising a liquid, electrodes having electrode surfaces immersed therein, one of said electrode surfaces having an aperture opposite to the center of the other electrode surface, means for producing a continuous flow of said liquid 125 130

through said aperture against the nearer surface of said other electrode, and for producing a continuous flow of said liquid against its other surface.

5. An oscillator comprising an optically active liquid, electrodes having electrode surfaces immersed therein, one of said electrode surfaces having an aperture opposite to the center of the other electrode surface, 10 means for producing a continuous flow of said liquid through said aperture, and means for cooling said liquid.

6. An oscillator comprising alcohol, electrodes having electrode surfaces immersed 15 therein, one of said electrode surfaces having an aperture opposite to the center of the other electrode surface, means for producing a continuous flow of said liquid through said aperture against the nearer

surface of said other electrode, and for producing a continuous flow of said liquid against its other surface. 20

7. An oscillator comprising alcohol, electrodes having electrode surfaces immersed therein, one of said electrode surfaces having an aperture opposite to the center of the other electrode surface, means for producing a continuous flow of said alcohol through said aperture, and means for cooling said alcohol. 25

30 In testimony whereof I have hereunto set my hand in the presence of two subscribing witnesses.
